EDWIN N. PREBLE, OF BEVERLY, MASSACHUSETTS, ASSIGNOR TO UNITED SHOE MACHINERY COMPANY, OF PATERSON, NEW JERSEY, A CORPORATION OF NEW JERSEY.

SOLE-PRESSING MACHINE.

1,193,186.

Specification of Letters Patent.

Patented Aug. 1, 1916.

Application filed May 31, 1911. Serial No. 630,294.

To all whom it may concern:

Be it known that I, EDWIN N. PREBLE, a citizen of the United States, residing at Beverly, in the county of Essex and State 5 of Massachusetts, have invented certain new and useful Improvements in Sole-Pressing Machines; and I do hereby declare the following to be a full, clear, and exact description of the invention, such as will enable 10 others skilled in the art to which it appertains to make and use the same.

This invention relates to sole pressing machines, and more particularly to sole pressing machines comprising complementary sole molding forms for operating upon the sole before the sole is incorporated in the shoe. In machines of this class, the sole molding forms are arranged for relative movement to produce pressure in molding 15 a sole and to afford clearance to permit the removal of the molded sole and the placing of another sole on the sole supporting form. Machines of this class are usually provided with sole gripping devices to prevent the 20 displacement of the sole during the relative pressure producing movement of the forms and with gaging devices to enable the sole to be accurately positioned on the sole supporting form.

30 One object of the present invention is to provide sole pressing machines of the class referred to with sole gripping and gaging devices which are simpler in construction and arrangement than those which have 35 heretofore been devised and which are operated in an improved and simplified manner.

In accordance with this object, one feature of the invention contemplates the provision of means controlled by the relative 40 pressure producing movement of the forms to actuate the gripping device to grasp the sole and hold it in position during the operation of the forms thereon.

45 A further feature contemplates the provision of means controlled by the relative clearance producing movement of the forms to actuate the gripping device to release the sole.

50 Certain other features of the invention relate to improvements in the construction, arrangement and mode of operation of the gaging devices for determining the position of the sole with relation to the forms.

55 In the drawings illustrating the invention

in the best form at present known to the inventor: Figure 1 is a partial side elevation of a sole molding machine embodying the invention; Fig. 2 is a side elevation of a portion of the mechanism shown in Fig. 1, 60 illustrating particularly the lower molding form and the gripping and gaging devices associated therewith; Fig. 3 is a front elevation of the mechanism illustrated in Fig. 2; Fig. 4 is a detail front elevation illustrating particularly the heel gage and the mechanism for adjusting the same; Fig. 5 is a detail plan view also illustrating the heel gage and the adjusting mechanism therefor; Fig. 6 is a detail side elevation of the 70 mechanism illustrated in Fig. 5.

The machine in which the present invention is embodied, a portion of which is illustrated in the drawings, is a double machine, being provided with two sets of coöperating 75 sole pressing forms substantially identical in structure, arrangement and mode of operation. The upper forms are stationary, and the lower forms are reciprocated simultaneously in opposite directions toward and 80 from the upper forms to produce pressure and afford clearance. Since the structure and arrangement of the two sets of forms, and the actuating mechanisms therefor are the same, and since the gaging and gripping 85 devices associated with the lower forms are duplicates of each other, the illustration and description of a single set of forms is considered sufficient to give a clear understanding of the invention.

The upper form, illustrated in the drawing, is indicated at 1 and is removably mounted in the usual manner upon a stationary cross head 2 of the frame.

3 indicates the lower or sole supporting 95 molding form, which is removably mounted upon a vertically reciprocating cross head 4 arranged to move upon guide rods 5. The sole supporting form 3 is adjustable vertically upon the cross head 4 so as to enable soles of different thicknesses to be molded 100 properly. The molding form 3 may be vertically adjusted by means of a wedge block 6 engaging said form, and adjusted longitudinally thereof by a rod 7 journaled 105 in the bearing 8 formed on the cross head and threaded into said block, said rod being operated by a hand wheel 9. Reciprocating movements are imparted to the cross head 4 to move the lower form toward and from 110

the upper form to produce pressure and clearance by means of toggle levers 10 connected with a link 11 operated by a crank shaft 12.

- 5 In order to enable the operator to position accurately the sole with respect to the lower molding form, the machine is provided with a heel gage indicated at 13. The gage is formed with two sole engaging flanges 14 arranged approximately at right angles to each other and a web 15 spanning the space between the flanges and provided with a recessed portion 16 to receive the fixed jaw of a sole gripping device to be 10 hereinafter described. When the sole is placed in position upon the lower molding form, the heel portion thereof is positioned with its rear edge engaging the flanges 14 and the lower face of the sole engages and 15 is supported by the web 15.

It is customary to use the same set of molding forms for several sizes of soles, and in order to permit the heel gage to be adjusted longitudinally of the sole supporting 20 form 3 for soles of different sizes, the gage is mounted to slide upon a guide bar 17 carried by an arm 18 of a bracket 19 secured to the cross head 4 and is held on said guide bar by means of a plate 20. The heel gage 25 is adjusted longitudinally of the sole supporting form by means of a threaded rod 21 engaging a threaded perforation in a lug 22 carried by the heel gage, and arranged to rotate in a bearing 23 formed upon the 30 arm 18 of bracket 19. The said rod carries at its rear extremity a pinion 24 which constitutes one member of a train of speed increasing gears 25, 26, 27, 24 arranged as shown particularly in Figs. 4, 5 and 6. The 35 gear 25 is fixed upon a stud shaft 28 journaled in a bearing in the arm 18. Fixed to the forward extremity of this shaft is an operating arm 29 by which the shaft may be manually rotated. The heel gage is adjusted 40 longitudinally of the sole supporting form by rotating the shaft 28 and thereby imparting through the speed increasing gears 25, 26, 27, 24 an increased rotary movement to the rod 21.

- 45 In order to enable the operator to adjust the heel gage accurately, a scale disk 30 is loosely mounted on the shaft 28 to the rear of the arm 29 and is held from turning with the shaft by means of a latch 31 pivoted at 50 32 on the arm 18 of the bracket 19, the forward extremity of which latch is arranged to engage one of a series of notches 33 in the disk 30, and is held in engagement with the notch by means of a spring 34. Upon 55 the front face of the disk 30 is a series of numbers corresponding to the various sizes of different classes of shoes, and a hand or indicator 35 is formed on the operating arm 29. The soles of different styles of shoes of 60 the same class vary somewhat in length and

the notches 33 in the disk 30 enable the disk to be adjusted to accommodate these variations. When the operator is about to mold a lot of soles of a certain class and style, he first takes a sole from the lot, 70 places this sole in the desired position on the sole supporting form, and adjusts the heel gage so that the heel of the sole is properly engaged by the flanges 14. The disk 30 is then adjusted so that the indicator 35 75 is opposite the number on the scale corresponding to the size of the sole. When the disk is thus properly adjusted for the particular class and style of soles that are to be molded, the heel gage may be accurately 80 adjusted for any size of this class and style by moving the indicator 35 until it is opposite the number of the scale corresponding to that particular size. The speed increasing gears for transmitting movement from 85 the shaft 28 to the rod 21 enable the heel gage to be adjusted quickly since it is necessary to impart to the shaft 28 less than a complete rotation to adjust the gage for any 90 style and size of shoe. By reason of the provision of these gears, a scale plate provided with a single series of size numbers about the circumference thereof may be employed so that confusion in the use of the adjusting 95 means is avoided.

The gripping device for gripping and holding the sole in position during the operation of the molding forms thereon in the present embodiment of the invention comprises a fixed jaw 36 formed on the guide 100 bar 17, and a movable jaw 37 arranged to move toward and from the fixed jaw to grasp and release the sole. The movable jaw 37 is carried by a lever 38 pivoted upon a pin 39 carried by spaced ears 40 formed 105 on the arm 18 of the bracket 19. When the movable jaw 37 is closed upon the fixed jaw 36, the heel of the sole is gripped by said jaws and held in position on the sole supporting form.

The mechanism for actuating the movable jaw 37 in the construction illustrated in the drawing comprises a rock shaft 41 mounted in bearings 42 and 43 formed respectively in the bracket 19 and in a second 115 bracket 44 also secured to the cross head 4. A lever 45 is attached to this rock shaft and is connected at its extremity with a rearwardly projecting arm 46 on the lever 38 by means of a ball ended link 47, the ball shaped 120 extremities of which are held and operate in sockets in the arm 46 and in the lever 45 respectively. By means of this construction, when the rock shaft 41 is rocked in its bearings, the movable jaw of the gripping device is moved toward and from the fixed jaw 125 thereof. In order to actuate the rock shaft, an operating arm 48 is secured thereto which is operated during the reciprocating movements of the cross head 4 by a cam plate 49 130

secured to one of the side standards of the machine in alignment with the arm 48. The cam plate 49 is formed with a surface 50 substantially parallel to the direction of movement of the cross head and with cam surfaces 51 and 52 arranged to engage the extremity of the arm 48 upon upward and downward movement of the cross head 4. When the cross head is in its lowermost position, the extremity of the arm 48 rests in the recess formed between the cam surfaces 51 and 52 as shown particularly in Fig. 3. When the cross head is moved upwardly to carry the lower molding form 10 toward the upper form to produce pressure upon a sole, the extremity of the arm 48 first engages with the cam surface 51, thereby rocking the shaft 41 and actuating the movable jaw 37 to grasp the sole supported 20 upon the lower form. Further upward movement of the cross head 4 carries the extremity of the arm 48 into engagement with the surface 50 of the cam plate and the movable jaw of the gripping device is thereby 25 maintained in gripping relation with the fixed jaw thereof during the operation of the molding forms on the sole. When the cross head is moved downwardly to carry the lower molding form away from the 30 upper form to produce clearance, the engagement of the extremity of arm 48 with the surface 50 of cam plate 49 maintains the movable jaw of the gripping device in gripping relation with the fixed jaw of said device until the cross head 4 executes its final 35 downward movement when the extremity of the arm 48 contacts with the cam surface 52 thereby rocking the shaft 41 in the opposite direction and opening the jaws of the gripping device to release the sole.

The sole gripping mechanism above described is simple in construction, certain and reliable in operation, and is capable of general application to sole molding machines, 45 since it is operated by the relative pressure and clearance producing movements of the molding forms.

The side gage for determining the position of the edge of the sole with respect to the 50 sole supporting form indicated at 53, is mounted on and preferably formed integral with the inturned upper end of an arm 54 secured to a supporting arm 55 carried by a sleeve 56 mounted on the rock shaft 41. 55 In order to permit the side gage to be adjusted to correspond with the different positions of adjustment of the lower molding form, the arm 54 is secured to the supporting arm 55 by means of a clamping screw 60 57 passing through a slot in the supporting arm and screwed into the arm 54. To provide for the adjustment of the side gage longitudinally of the lower form so that the gage may be properly positioned for forms 65 of different sizes, the sleeve 56 is split length-

wise for a short distance and is clamped in adjusted position upon the rock shaft 41 by means of a wedge nut 58.

From the foregoing description, it will be evident that upon the upward or pressure 70 producing movement of the lower molding form, the side gage will be carried by the movement of the rock shaft 41 beyond the edge of the lower form so that it will not be crushed by the forms as they are brought 75 together. When the lower form is moved away from the upper form to produce clearance, the movement of the rock shaft 41 carries the side gage into contact with the acting face of the lower form. By providing 80 a common operating mechanism for actuating the gripping jaws and the side gage, the operating mechanism for these devices is rendered simpler and more compact.

Since substantially the entire mechanism 85 of the gaging and gripping devices is carried by the brackets 19 and 40 secured to the cross head 4, these devices may be readily applied to molding machines of the various types at present in common use. The said 90 devices are also independent of the molding forms so that the said forms may be placed in the machine and removed without disturbing the gaging and gripping devices.

Having explained the nature and object 95 of the invention and having specifically described one form of mechanism in which it may be embodied, what is claimed is:—

1. A sole pressing machine, having, in combination, complemental sole molding forms, means for relatively moving said forms to produce pressure and clearance, a sole gripping device mounted beyond the forms and bodily immovable with relation to one of the forms to grip the sole after it 100 has been located with relation to the forms, and means controlled by the relative pressure producing movement of said forms to actuate said device to grasp the sole as the forms are brought together and hold it in 105 position until the sole is engaged between the forms.

2. A sole pressing machine, having, in combination, complemental sole molding forms, means for relatively moving said 115 forms to produce pressure and clearance, a sole gripping device mounted beyond the forms and bodily immovable with relation to one of the forms to grip the sole after it has been located with relation to the forms and hold it in position as the forms are brought together until the sole is engaged between the forms, and means controlled by the relative clearance producing movement of said forms to actuate said device to release the sole.

3. A sole pressing machine, having, in combination, complemental sole molding forms, means for relatively moving said 130 forms to produce pressure and clearance, a

sole gripping device mounted beyond the forms and bodily immovable with relation to one of the forms to grip the sole after it has been located with relation to the forms, and means controlled by the relative pressure and clearance producing movements of said forms to actuate the gripping device to grasp the sole and hold it in position as the forms are brought together until the sole is engaged between the forms and to release the sole as the forms are moved relatively to positions of clearance.

4. A sole pressing machine having, in combination, complemental sole molding forms, means for relatively moving said forms to produce pressure and clearance, a sole gripping device bodily immovable with relation to one of the forms to grip the sole after it has been located with relation to the forms and hold it in position as the forms are brought together until the sole is engaged between the forms, a side gage associated with one of said forms and arranged to move toward and from the acting face thereof, and means controlled by the relative pressure producing movement of said forms to actuate the gripping device to grasp the sole and to move the side gage beyond the edge of the forms.

5. A sole pressing machine having, in combination, complemental sole molding forms, means for relatively moving said forms to produce pressure and clearance, a gripping device bodily immovable with relation to one of the forms to grip the sole after it has been located with relation to the forms and hold it in position as the forms are brought together until the sole is engaged between the forms and a side gage associated with one of said forms, and means controlled by the relative clearance producing movement of said forms to actuate the gripping device to release the sole and to move the side gage into engagement with the acting face of said last mentioned form.

6. A sole pressing machine having, in combination, complemental sole molding forms, means for relatively moving said forms to produce pressure and clearance, a gripping device bodily immovable with relation to one of the forms to grip the sole after it has been located with relation to the forms and hold it in position as the forms are brought together until the sole is engaged between the forms and a side gage associated with one of said forms, and means operated by the relative pressure and clearance producing movements of said forms to actuate the gripping device to grasp and release the sole and to move the side gage beyond the edge of and into engagement with the acting face of said last mentioned form.

7. A sole pressing machine having, in

combination, complemental sole molding forms, means for relatively moving said forms to produce pressure and clearance, a gripping device arranged to grasp and release the sole, a side gage arranged to move toward and from the acting face of one of said forms and actuating mechanism common to both the gripping device and the side gage.

8. A sole pressing machine comprising a sole supporting form, a heel gage for determining the position of the sole with respect to the supporting form, mechanism for adjusting the gage longitudinally of the form comprising a threaded rod, a member threaded on the rod, an indicator, a series of speed increasing gears connected with the indicator for relatively turning the rod and member, a connection for moving the gage from the relative movement of the rod and said member longitudinally of the rod, and a scale-plate coöperating with the indicator to indicate the size of the sole for which the gage is adjusted.

9. A sole pressing machine comprising a sole supporting form, a heel gage for determining the position of the sole with respect to the supporting form, mechanism for adjusting the gage longitudinally of the form comprising a threaded rod, a member threaded on the rod, an indicator, a series of speed increasing gears connected with the indicator for relatively turning the rod and member, a connection for moving the gage from the relative movement of the rod and said member longitudinally of the rod, a scale-plate coöperating with the indicator to indicate the size of the sole for which the gage is adjusted, and provision for adjusting the scale-plate.

10. A sole pressing machine having, in combination, complemental sole molding forms, means for relatively moving said forms to produce pressure and clearance, sole gripping jaws bodily immovable with relation to one of the forms to grip the sole after it has been located with relation to the forms and hold it in position as the forms are brought together until the sole is engaged between the forms, a rock shaft arranged to actuate said jaws to grasp and release the sole, an operating arm fixed to said shaft, and a cam plate fixed to the machine frame and arranged to engage said arm and operate the same during the relative pressure and clearance producing movements of said forms.

11. A sole pressing machine having, in combination, complemental sole molding forms, mechanism for relatively moving said forms to produce pressure and clearance, sole gripping jaws bodily immovable with relation to one of the forms to grip the sole after it has been located with relation to the forms for holding the sole in position

- on the sole supporting form, and mechanism acting automatically to relatively actuate the gripping jaws during the initial relative pressure producing movement of said forms to grasp the sole and to maintain the said jaws in sole gripping relation until the forms approach the end of their relative clearance producing movement, said mechanism being constructed and arranged to actuate the gripping jaws to release the sole during the final relative clearance producing movement of the forms.
12. A sole pressing machine having, in combination, complemental sole molding forms, sole gripping jaws for holding the sole on the sole supporting form, a rock shaft arranged to relatively actuate said jaws, a side gage mounted on said rock shaft, and means to operate said rock shaft during the relative pressure and clearance producing movements of said forms.
13. A sole pressing machine, having, in combination, complemental sole molding forms, means for relatively moving said

forms toward and from substantially alined positions of clearance to produce clearance and pressure, a sole gripping device, and means controlled by the relative movement of said forms from substantially alined positions of clearance to positions of pressure to actuate said device to grasp the sole and hold it in position until the sole is engaged between the forms.

14. A sole pressing machine, having, in combination, complemental sole molding forms, means for relatively moving said forms toward and from substantially alined positions of clearance to produce clearance and pressure, a sole gripping device, and means controlled by the relative movement of said forms toward substantially alined positions of clearance to actuate said device to release the sole.
